UNITED STATES PATENT OFFICE

95,399

DESIGN FOR A SHOE

Tycho Buek, Jr., Philadelphia, Pa., assignor to Golo Slipper Company, Inc., New York, N. Y., a corporation of New York

Application February 11, 1935, Serial No. 55,329

Term of patent 7 years

To all whom it may concern:

Be it known that I, Tycho Buek, Jr., a citizen of the United States, residing in Philadelphia, county of Philadelphia, and State of Pennsylvania,
have invented a new, original, and ornamental Design for a Shoe, of which the following is a specification, reference being had to the accompanying drawing, forming a part thereof.

In the drawing:

Fig. 1 is a plan view of a shoe showing my new design.

Fig. 2 is a side elevation thereof.

I claim:

The ornamental design for a shoe substantially as shown.

TYCHO BUEK, JR.
